UNITED STATES PATENT OFFICE.

ISAAC HARTER, OF DONGAN HILLS, NEW YORK, ASSIGNOR, BY MESNE ASSIGNMENTS,
TO FULLER LEHIGH COMPANY, A CORPORATION OF DELAWARE.

FURNACE.

Application filed May 26, 1925. Serial No. 32,897.

My present invention relates to furnaces, particularly when such furnaces are provided with air-cooling ducts formed between a pair of parallel walls spaced apart, and will be best understood from the following description and the annexed drawings in which Fig. 1 is a vertical section of one form of furnace which I have chosen for purposes of illustration of my invention; Fig. 2 is an enlarged view of a portion of Fig. 1, and Fig. 3 is a plan view of the parts shown in Fig. 2.

Like reference characters indicate like parts throughout the drawings.

For purposes of illustration, I have chosen a typical form of combustion chamber, such as is commonly used with a steam boiler, in which the fuel is powdered coal. In the drawings, the combustion chamber 10 has a steam boiler 11 positioned above it, the fuel being projected downward into the combustion chamber 10 by a burner 12. The walls are provided with horizontal air ducts leading to openings 13 in the front wall by which the combustion air is supplied to the fuel, the air being forced into these ducts by a fan 14 through a main duct 15 and a plurality of lateral ducts 16. The horizontal air ducts extend through the rear and side walls and into a chamber in the front wall in a well-known manner, the air flowing from the ducts 16 into these horizontal ducts and from thence around the walls into the openings 13.

In the arrangement illustrated, the rear and side walls have the same general construction, and a description of the rear wall only will be sufficient to make an understanding of my invention complete. The rear wall is made up of a pair of vertical parallel walls 17, 18, spaced apart. It will be understood that the walls 17 and 18 may be inclined and that by the term "vertically disposed" as used in the appended claims, I mean either a wall which is vertical, as shown in the drawings, or somewhat inclined to the vertical to form a hopper-shaped furnace chamber.

In the construction of such double walls, there is no difficulty by the use of known methods in maintaining the outer wall 18 against bulging inward or outward when subjected to variations in heating. By reason of the position of the inner wall 17, however, the maintenance of this inner wall is difficult.

In the illustrative arrangement, I have provided a plurality of courses of special brick 19, 20, each of which has a shallow recess

formed on a horizontal face near one end of the brick, this shallow recess merging into a deeper recess toward the middle of the brick. When the two brick 19 and 20 are placed together, as shown best in Fig. 2, these recesses form a T-shaped recess between the brick. The brick in the walls 17 and 18 are laid so that the courses of special brick 19, 20 come approximately opposite each other.

Extending between the walls 17 and 18 across the space between such walls, I provide a plurality of flexible metallic members to engage the above referred to recesses, so as to maintain the walls 17 and 18 in spaced relation. In the form illustrated, these flexible metallic members are shown as thin metallic plates 21, each having an enlarged head 22 on its opposite edges. In each of the horizontal grooves or recesses formed in the walls 17 and 18, I preferably provide a plurality of these plates 21 edge to edge to serve not only as holding members, but also as means for dividing the space between the walls 17 and 18 into a plurality of horizontal air ducts. Preferably, the plates 21 are normally spaced apart somewhat and the space between such plates may be conveniently covered by a cover plate 23 lying over such space and held against disarrangement by pins 24 projecting into the space between the plates 21, 21. As many of the cover plates 23 as may be necessary are provided and, if desired, one can be provided between each pair of plates 21.

It will be obvious from the arrangement just described that the walls 17 and 18 or any portion thereof may move both laterally and longitudinally in relation to each other while, at the same time, the members 21 prevent the wall 17 from bulging in relation to the wall 18, so that, if the latter is held against bulging, then the wall 17 will be correspondingly held. The vertical motion between the walls is permitted by the flexing of the plates 21 and the horizontal motion by the sliding of these plates and their heads 22 in the grooves which I provide in the special brick 19 and 20.

It will be understood that the arrangement which I have shown is merely illustrative and that the embodiment of my invention may be widely varied. It will also be understood that some of the features of my invention may be used independently of other features. However, the flexible metallic members may be used as tie members only and, in such case, need be only relatively narrow. It will also

be understood that while I have shown these tie pieces dividing the space between the walls into horizontal ducts, the same arrangement may be used in dividing such space into vertical ducts. It will also be understood that for some purposes, the flexible metallic members may be used for holding a single wall against bulging, in which case, the end of the plate connected to the wall 18 would be attached to any other fixed member, such as a buckstay or a beam connected to a buckstay.

It will further be understood that the thin metallic members will be maintained in spite of the fact that they are connected to a highly heated wall, because of an air space around them through which the relatively cool combustion air is flowing. It will also be understood that as many courses of the special brick 19, 20 may be used, as desired, the remainder of the wall being made up of the refractories usually used for that purpose.

I claim:

1. A furnace having a pair of parallel, vertically-disposed walls spaced apart, and flexible metallic plates placed substantially edge to edge and connected to the walls and extending across the space between them to hold said walls in alinement.

2. A furnace having a pair of parallel, vertically-disposed walls spaced apart, and flexible metallic members connected to the walls and extending across the space between them to hold said walls in alinement, said members having a head at each end engaging grooves in the walls, the grooves being longer than the heads, whereby one wall may shift relatively to the other in the direction of the grooves and also at right-angles to the direction of the grooves by the flexing of said members.

3. A furnace having a pair of parallel, vertically-disposed walls spaced apart, and flexible metallic members connected to the walls and extending across the space between them to hold said walls in alinement, said members comprising thin metallic plates placed substantially edge to edge and spaced apart to form air ducts in the space between said walls.

4. A furnace having a pair of parallel, vertically-disposed walls spaced apart, and flexible metallic members connected to the walls and extending across the space between them to hold said walls in alinement, said members comprising thin metallic plates spaced apart to form air ducts in the space between said walls and each member having a head on each edge engaging a groove in one of the walls, the grooves being longer than the heads, whereby one wall may shift relatively to the other in the direction of the grooves and also at right-angles to the direction of the grooves by the flexing of said members.

5. A furnace having a pair of parallel,

vertically-disposed walls spaced apart, each of said walls having a plurality of horizontal grooves in its face adjacent the other wall, said grooves having an enlarged space at its end away from the other wall, a plurality of thin metallic members spaced along each groove, each member extending into a pair of opposite grooves in the wall and having a head on each edge engaging the enlarged space of the groove with said head shorter than the groove with which it engages.

6. A furnace having a pair of parallel, vertically-disposed walls spaced apart, each of said walls having a plurality of horizontal grooves in its face adjacent the other wall, said grooves having an enlarged space at its end away from the other wall, a plurality of thin metallic members spaced along each groove, each member extending into a pair of opposite grooves in the wall and having a head on each edge engaging the enlarged space of the groove, the members in each groove being spaced apart and cover pieces, each extending over a space between a pair of said members, whereby a series of air ducts is formed in the space between said walls.

7. A furnace having a pair of parallel, vertically-disposed walls spaced apart, each wall having a plurality of courses of special brick spaced apart, each of said special brick having a shallow recess in its horizontal face at the end adjacent the space between the walls and a deeper recess at the inner end of said shallow recess, and said special brick being laid in courses to bring the recesses of adjacent courses together to form a T-shaped recess extending into the wall from the space between the walls, and thin metallic members having T-shaped heads on each edge, each of said heads engaging a T-shaped recess in one of the walls and being shorter than the recess with which it engages and said members extending across the space between the walls.

8. A furnace having a pair of parallel, vertically-disposed walls spaced apart, each wall having a plurality of courses of special brick spaced apart, each of said special brick having a shallow recess in its horizontal face at the end adjacent the space between the walls and a deeper recess at the inner end of said shallow recess, and said special brick being laid in courses to bring the recesses of adjacent courses together to form a T-shaped recess extending into the wall from the space between the walls, and thin metallic members having T-shaped heads on each edge, each of said heads engaging a T-shaped recess in one of the walls and being shorter than the recess with which it engages and said members extending across the space between the walls, said members being relatively wide and dividing the space between said walls into a plurality of parallel air ducts.

9. A furnace having a pair of parallel, vertically-disposed walls spaced apart, each wall having a plurality of courses of special brick spaced apart, each of said special brick having a shallow recess in its horizontal face at the end adjacent the space between the walls and a deeper recess at the inner end of said shallow recess, and said special brick being laid in courses to bring the recesses of adjacent courses together to form a T-shaped recess extending into the wall from the space between the walls, thin metallic members having T-shaped heads on each edge, each of said heads engaging a T-shaped recess in one of the walls and being shorter than the recess with which it engages and said members extending across the space between the walls, said members being relatively wide with their edges spaced apart, and a cover piece over the space between each pair of said members.
10. A furnace having a vertically-disposed
- wall, a fixed structure outside said wall and spaced therefrom, and flexible metallic members connected to the wall and to said fixed structure, said members being arranged to bend easily in one direction and to slide relatively to said wall and said structure in another direction, whereby the wall is free to move in any direction in the plane of its face and is held against motion at right-angles to such plane.
11. A furnace having a pair of parallel, vertically disposed walls spaced apart, flexible metallic members connected to the walls and extending across the space between them to hold said walls in alinement, said members comprising thin metallic plates spaced apart to form air ducts in the space between said walls, the adjacent edges of said plates being spaced apart, and cover plates disposed over said spaces.

ISAAC HARTER.
